CATALYTIC REFORMING WITHOUT THERMAL CRACKING

Kenneth M. Elliott, Woodbury, N. J., assignor to Socony Mobil Oil Company, Inc., a corporation of New York

Application May 1, 1952, Serial No. 285,482

7 Claims. (Cl. 196—50)

The present invention relates to catalytic reforming and, more particularly, to catalytic reforming wherein the major portion of the heat required is supplied by the vapor stream without substantial thermal cracking of the charge stock, and without an intermediate heating of the charge stock.

The present invention relates to a catalytic reforming process in which the reforming catalyst is passed cyclically to a reactor and a regenerator. In the reactor the reforming catalyst passes successively through at least two reforming zones. For several reasons in such a reforming operation it is desirable, if not necessary, to supply substantially all of the sensible heat in the vapor feed stream. When it is necessary to reform naphtha under severe conditions, i. e., high temperature level and relatively high endothermic heat requirement, to make super octane number motor gasolines or aviation blending stocks in a single straight through reformer, it would be necessary either to preheat the charge stock vapor to a temperature which would cause considerable thermal cracking in the preheating furnaces and transfer lines in order to provide in the vapor stream sufficient heat for the reforming reaction, or it would be necessary to reheat the reactant after partial conversion, i. e., subject the charge stock to an intermediate heating step, and then re-inject the charge stock into the reformer to complete the conversion.

It has been found that the foregoing undesirable alternatives can be avoided by operating a single reactor with the feed distributed between an upper reforming zone and a lower reforming zone through which the catalyst passes successively, or two reactors through which the catalyst passes successively under such conditions that the vapor feed is heated to a temperature above the reforming temperature but below a temperature at which substantial thermal cracking occurs, the heat capacity of the vapor stream is controlling of the temperature in the first reforming zone which the catalyst enters, the vapor passing to the said first zone carries with it more heat than is required for the degree of reforming desired in said first zone and the excess heat in the vapor supplied to said first zone is transferred to the catalyst flowing

therethrough, and the transferred heat carried by the catalyst into the second reforming zone where it is used to help effect the severer reforming reaction desired therein. Accordingly, the more severe reforming operation is conducted in the second zone which the catalyst enters while the heat for the total reforming is supplied by the vapor feed without thermal cracking thereof and without the necessity for reheating the charge during its conversion.

Accordingly, it is an object of the present invention to provide a method of reforming non-aromatic and substantially non-aromatic mixtures of hydrocarbons in which substantially all of the heat required for the reaction is supplied in the charge mixture vapors without substantial thermal cracking of the charge stock and without reheating of the charge stock during conversion. It is another object of the present invention to provide a method of reforming non-aromatic or substantially non-aromatic mixtures of hydrocarbons in which the catalyst flows successively through two reforming zones. The vapors passing into the first reforming zone which the catalyst enters carry with them more heat than is required for the degree of reforming desired in said first zone and the excess heat in the vapor supplied to said first zone is transferred to the catalyst flowing therethrough, and the transferred heat carried by the catalyst into the second reforming zone where it helps to effect the reforming reaction desired therein. Other objects and advantages will become apparent from the following discussion taken in conjunction with the drawings in which

Figure 1 is a schematic flow diagram of a two reforming zone split-feed reactor;

Figure 2 is a diagrammatic illustration of two reactors in series which can replace the single reactor of Figure 1;

Figure 3 is a diagrammatic illustration of a multifeed inlet reactor which can replace the reactor of Figure 1 wherein the volume of the two catalyst beds forming the two reforming zones can be varied whilst simultaneously controlling the distribution of charge stock to the two reforming zones so formed;

Figure 4 is a diagrammatic illustration of a single reactor with a plurality of charge mixture inlets whereby the depth of the catalyst beds in the two reforming zones can be complementally varied whilst simultaneously controlling the distribution of two charge stocks between the two reforming zones so formed; and

Figure 5 is a diagrammatic illustration of a reactor having two reforming zones in which the ratio of recycle gas to charge stock can be varied.

In general, the method of reforming a non-aromatic or substantially non-aromatic mixture of hydrocarbons such as a straight-run or virgin naphtha, a cracked naphtha or a mixture of straight-run and cracked naphthas, as disclosed hereinafter, is used employing the conditions listed in Table I.

3

Vapor flow to upper zone, percent	95-25	85-50	
Catalyst Bed above Reactor Inlet, Volume percent	80-20	70-30	
Heat Transferred from Upper Zone Vapors to lower zone, B. t. u./lb. vapor to lower zone ¹	4.0-125		
Utilization efficiency of heat transferred to lower zone, percent ²	100-20	100-30	15
Amount of lower zone heat requirement supplied by upper zone vapors, percent ³	>5	>20	
Vapor Stream Heat Capacity/Catalyst Stream Heat Capacity (upper zone)	0.7-40	0.9-25	
<i>Kiln</i>			
Temperature, ° F.	600-1,400	700-1,000	
Pressure, p. s. i. a.	15-600	15-35	20

¹ The total heat transferred from the vapors entering the upper zone to the bottom zone is calculated by the following equation:

$$HT = \frac{(T_1 - T_2)(C_p)(P)}{R}$$

where,

HT is heat transfer, B. t. u./lb. of vapor to lower zone.
T₁ is temperature of catalyst leaving upper zone, ° F.

T₂ is temperature of catalyst entering upper zone, ° F.

C_p is specific heat of vapors, B. t. u./lb./° F.

R is Vapor Stream Heat Capacity/Catalyst Stream Heat Capacity for upper zone.

P is lbs. of vapor to upper zone/lbs. of vapor to lower zone.

² The utilization efficiency of heat transferred to lower zone can be calculated from the following equation:

$$E = \frac{(T_1 - T_2)}{(T_1 - T_3)} (100)$$

where,

E is efficiency, percent.
T₁ is temperature of catalyst leaving upper zone, ° F. (enters lower zone).

T₂ is temperature of catalyst entering upper zone, ° F.

³ The amount of lower zone heat requirement supplied by the vapors passing through the upper zone, percent can be calculated from the following equation:

$$X = \frac{(HT)(E)}{HR}$$

where,

HT is heat transfer as calculated above;

E is utilization efficiency as calculated above;

HR is heat requirement of the lower zone, BT U/lb. vapor, and
X is percent of lower zone heat requirement supplied by vapors passing through the upper zone.

15 Space velocity, as used herein, is the number of volumes of liquid charge stock passing through the reactor per hour per volume of catalyst holdup in the reactor. As will become manifest hereinafter, the space velocities in both zones are not always equal and in fact usually are different.

The ratio of vapor stream heat capacity to catalyst stream heat capacity, i. e., VSHC/CSHC is the numerical value of the ratio of the product of the pounds of vapors per hour and the specific heat thereof to the pounds of catalyst per hour and the specific heat thereof.

Distribution of the vapors in controlled amounts to the two zones is obtained by throttling devices restricting the flow of reformatre from the two zones.

30 The advantage of the present method of reforming employing a split-bed, split-flow reactor over the once through single-bed reactor is recognized immediately upon study of the data presented in Table II.

*VSHC/CSHC is the ratio of the product of the pounds of vapor entering the first reforming zone and the specific heat thereof to the product of the pounds of catalyst entering the first reforming zone and the specific heat thereof.

While an increased yield of 0.8 per cent to 5.2 per cent, percentagewise, appears small, it represents an increased income of about 120 to about 780 barrels per stream day on a 15,000 BPSD unit.

The data presented in Table II established the effect

in Table III show the effect of the distribution of charge mixture between the zones at a given VSHC/CSHC.

The data presented in Table III show the marked effect of the distribution of the vapors in catalyst beds of equal volumes upon the yield of high octane rating gasoline.

In Table IV are presented data showing the effect of

*VSHC/CSHC is the ratio of the product of the pounds of vapor entering the first reforming zone and the specific heat thereof to the product of the pounds of catalyst entering the first reforming zone and the specific heat thereof.

The data presented in Table IV show that, with other variables such as VSHC/CSHC, vapor split and overall space velocity constant, the volume of catalyst in the reforming zone of greater severity has a marked effect upon the octane rating and yield of gasoline from that zone.

The data presented in Table V show the effect of VSHC/CSHC on the octane rating of the gasoline produced when different charge stocks are treated in the two reforming zones; the more refractory stock being charged to the zone of greater severity.

Gas-tight valve 12 is then closed, valves 17, 22 and 23 closed and valve 19 opened whereby pressuring gas such as recycle gas is introduced into pressuring chamber 13 through lines 61 and 48 until the pressure therein is at least that of reactor 24 and preferably about 5-10 p. s. i. a. higher. Gas-tight valve 14 then is opened and the catalyst flows into surge chamber 104. Valve 14 is closed and valve 23 then is opened and the residual gas in pressure chamber 13 is vented to a flare, not shown. This completes the cycle.

The catalyst flows from surge chamber 104 into and

*VSHC/CSHC is the ratio of the product of the pounds of vapor entering the first reforming zone and the specific heat thereof to the product of the pounds of catalyst entering the first reforming zone and the specific heat thereof.

The foregoing and similar results can be obtained by reforming the non-aromatic and/or substantially non-aromatic mixtures of hydrocarbons in the manner illustrated in the drawings. Referring to Figure 1, the course of the catalyst through the reactor and kiln will be followed first and then the course of the charge mixture will be followed through the reactor and auxiliary equipment.

Active catalyst at a temperature of about 100° to about 1100° F. and preferably at about 400° to about 800° F. is accumulated in reactor catalyst feed bin 11. Since the reactor is shown as operating at 190 p. s. i. a. although the reactor pressure can be 15-600 p. s. i. a. and preferably 100-300 p. s. i. a., a reactor sealing and catalyst transfer means is necessary. Any suitable device for transferring particles from a zone of one pressure to a zone of higher pressure can be used. For the purpose of illustration, a pressure lock formed between gas-tight valves 12 and 14 and including pressuring chamber 13 will be described. The pressure lock operates in a cyclic manner as follows:

With gas-tight valves 12 and 14 closed, pressure chamber 13 is purged with an inert and/or non-flammable gas such as flue gas drawn from a source, not shown, through pipes 15 and 16 under control of valve 17 with valve 19 closed and vented to a flare, not shown, through lines 20 and 21 under control of valves 22 with valve 23 closed. Valve 12 is opened and catalyst flows into pressuring chamber 13 to fill the chamber to a predetermined level.

downwardly through reactor 24 as a substantially compact column first contacting the upwardly flowing vapors of the charge mixture and then flowing concurrently with the vapors of the charge mixture. During passage through the reactor, the catalyst becomes spent and contaminated with a carbonaceous deposit. The spent catalyst leaves the reactor through a catalyst flow-control device such as throttle valve 25. When operating at pressures in excess of atmospheric and when the kiln is operating at a pressure below that of the reactor, it is preferred to transfer the spent catalyst from the reactor to a catalyst transfer means, whereby the spent catalyst is transported to the kiln, by any suitable means whereby solid particles can be transferred from a zone of high pressure to a zone of less pressure. The catalyst flows through catalyst flow control means 25 into surge tank 26 from which it is removed in any suitable manner as by a pressure lock.

The pressure lock formed between gas-tight valves 27 and 28 includes depressuring chamber 29 and operates in a cyclic manner similar to the pressuring lock at the top of the reactor previously described hereinbefore. Thus, with gas-tight valves 27 and 28 closed, depressuring chamber 29 is purged with an inert and/or non-flammable gas such as flue gas. The purge gas is drawn from a source not shown through pipes 30 and 31 under the control of valve 32 with valve 33 closed and vented to a flare, not shown, through pipes 34 and 35 with valve 36 open and valve 37 closed. Valves 32 and 36 are closed and pressuring gas such as recycle gas is drawn through pipes 38

and 31 with valve 33 open and introduced into depressuring chamber 29 until the pressure therein is that of the surge tank 26. Valve 33 is closed and gas-tight valve 27 opened. Catalyst flows into depressuring chamber 29 to fill it to a pre-determined level. Gas-tight valve 27 is closed, valve 37 opened and the gas in depressuring chamber 29 vented to a flare until the pressure in chamber 29 is reduced to that of the kiln or regenerator. Gas-tight valve 28 then is opened and the catalyst flows into surge chamber 105 and thence into chute 39. This completes the cycle.

The spent catalyst flows along chute 39 to any suitable catalyst transfer means suitable for transporting the spent catalyst to the kiln or regenerator. Suitable catalyst transfer means include gas-lifts and the like, elevators, etc. For purpose of discussion, an elevator 40 is illustrated. The catalyst flows along chute 39 to the boot 41 of bucket elevator 40 more fully described in U. S. Patent No. 2,409,596. The catalyst in elevator boot 41 is picked up by the elevator buckets and raised to the elevator head 42 where it is discharged into chute 43 along which it flows to spent catalyst hopper 44 atop of kiln or regenerator 45.

Kiln or regenerator 45 is of any suitable type wherein the carbonaceous deposit on the spent catalyst can be burned off in a stream of combustion supporting gas, such as air, at temperatures of about 600°-1400° and preferably at about 700°-1000° F. at pressures of 15-600 preferably 15-35 p. s. i. a. A suitable kiln is described more fully in U. S. Patent No. 2,469,332. However, the kiln 45 illustrated is provided with cooling coils represented by 46 through which water from drum 47 by means of pipes 48 and 49 is passed and returned to stream drum 47 through pipe 50.

The spent catalyst passes downwardly from hopper 44 through kiln 45 to chute 51 by means of which the regenerated or reactivated catalyst is carried to a suitable catalyst transfer device, such as a gas-lift or the like, or as illustrated, a bucket elevator 52 by means of which the active catalyst is raised to the reactor catalyst feed bin 11 ready for another cycle through the reactor and kiln.

Returning now to the reactor; the course of the reactant and reformate will be followed. A mixture of hydrocarbons containing hydrocarbons convertible to aromatic hydrocarbons such as a petroleum naphtha is drawn from a source not shown through line 106 and introduced into absorber 107 wherein the naphtha or charge stock contacts the make gas. Absorber 107 is of any type suitable for gas-liquid contact and stripping the gas of light hydrocarbons. The make gas is produced in the reactor during the reforming reaction. Through contact with the net gas make in absorber 107, the charge stock strips light hydrocarbons from the gas and leaves absorber 107 through line 53 and passes through heat exchanger 54 where it is in indirect heat exchange with the reformate. From heat exchanger 54, the charge stock passes by line 55 to charge stock heater 56 wherein the temperature of the charge stock is raised to a temperature above the reaction temperature but below that of thermal reforming or cracking. The temperature of the charge stock will usually be about 850° to about 1080° F. and preferably about 960°-1060° F. The charge stock leaves heater 56 through line 57.

The recycle gas is separated from the condensed hydrocarbons of the reformate in separator 59, leaves separator 59 by way of pipe 60 to pipe 61 where the net gas produced is passed through line 62 to absorber 107. After contact with the charge stock in absorber 107, as described hereinbefore, the stripped gas passes out of absorber 107 through pipe 63 to fuel gas holder 64.

The balance of the recycle gas in pipe 61 flows therethrough to pipe 65, passes through heat exchanger 66 wherein it is in indirect heat exchange with reformate and passes through pipe 67 to recycle gas heater 68.

In recycle gas heater 68 the recycle gas is heated to a

temperature such that when mixed with the charge stock to form a charge mixture, the charge mixture enters the reactor 24 at a temperature of about 850°-1080° F. and preferably about 960°-1060° F. To attain this end the recycle gas is heated in furnace 68 to about 1000° to about 1300° F.

The heated recycle gas leaves heater 68 through pipe 69. Heated charge stock in line 57 and heated recycle gas in pipe 69 are mixed in line 70 by regulation of valves 71 and 72 respectively to give a charge mixture containing charge stock and recycle gas in the mol ratio of 1-15 mols recycle gas to 1 mol of charge stock and preferably about 4 to about 10 mols of recycle gas per 1 mol of charge stock. The average molecular weight of the charge stock is determined in the usual manner from the ASTM distillation curve.

When the charge stock is to be reformed in the presence of hydrogen it is preferred to use a recycle gas containing about 25 per cent to about 80 per cent, and preferably about 35 per cent to about 60 per cent hydrogen, balance C₁ to C₆ hydrocarbons. Such a hydrogen-containing recycle gas is mixed with the charge stock in the ratio of about 1 to about 8, preferably about 2 to about 5 mols of hydrogen per mol of charge stock. The average molecular weight of the charge stock being determined in the usual manner from the ASTM distillation curve.

The charge mixture of charge stock and recycle gas enter reactor 24 through line 70 and its associated distributor not shown. The distributor can be of any type whereby the charge mixture can be spread over substantially the entire cross-section of reactor 24.

In the drawing, charge mixture inlet 70 is shown as being intermediate the ends of reactor 24 and at about the mid-point thereof. The location of the charge mixture inlet 70 at about the mid-point of reactor 24 divides the catalyst bed in reactor 24 into two beds of approximately equal volume; an upper bed U and a lower bed L. In order to introduce into the upper bed U more heat than is required for the degree of reforming desired in bed U and to provide for removal of the excess heat by the catalyst passing into bed L, it is necessary to regulate and control the distribution of the vapors of the charge mixture between the two beds. This control and regulation is obtained by throttling devices 73 and 74 in reformate outlet lines 75 and 76.

Throttling devices 73 and 74 are of any suitable type whereby the volume of vapors passing therethrough can be regulated. Throttle valves of conventional design have given satisfactory results. By means of throttling devices 73 and 74, the distribution of charge mixture vapors can be controlled dependent upon the degree of severity of reforming required in both reforming zones and in such a manner as to supply substantially all of the heat required in both zones for the reforming action. Accordingly, the ratio of the product of the pounds of charge mixture entering the reactor per hour and its specific heat, i. e., vapor stream heat capacity, to the product of the pounds of catalyst entering the reactor per hour, and its specific heat, i. e., catalyst stream heat capacity, is held within the limits of about 200 to about 0.5 and preferably within the limits of about 40 to about 1. In general, with the aforesaid ratio of vapor stream heat capacity (VSHC) to catalyst stream heat capacity (CSHC) in the upper reforming zone held within the limits of about 40 to about 0.7 and preferably about 25 to about 0.9, about 95 per cent to about 25 per cent, and preferably about 85 per cent to about 50 per cent of the vapors of the charge mixture will be passed upwardly and counter-currently to the catalyst passing through catalyst bed U and the balance downwardly and concurrently with the catalyst passing through bed L by setting valves 73 and 74 to produce the distribution of charge mixture vapors between beds U and L in accordance with the exigencies of the particular circumstances. As previously stated, catalyst rate can also be regulated by catalyst flow-control regulator 25.

The average space velocity, i. e., liquid volume of charge stock per hour per volume of catalyst in the reactor is about 0.1 to about 6.0 and preferably about 0.5 to about 2.0. However, as those skilled in the art will immediately recognize, the space velocity in the reforming zones U and L will vary dependent upon the division of the total catalyst volume and upon the distribution of the vapors of charge mixture between beds U and L. In general, however, when the same charge stock is being treated in both reforming zones, the space velocity in zone L preferably is lower than in zone U while for two different charge stocks when the less refractory charge stock is treated in zone L, the space velocity in the bottom zone can be as much as 3 times that of the other charge stock in zone U but will usually be lower in zone L than in zone U.

The reformate and gas produced during the reaction together with recycle gas leave zone U through line 75 under control of throttling device 73 while the reformate, make gas and recycle gas leave zone L through line 76 under control of throttling device 74. The effluents from both zones mix in line 77. It is to be observed at this point that when operating to produce gasolines of different octane ratings the reformates are kept separate and that when desired, as described in my co-pending application Serial No. 285,483, filed this same day, the make gas and recycle gas from each zone can be kept separate and a part or all of one bled off. Such alternatives are illustrated in Figures 2, 3 and 4.

The mixed effluents from zones U and L pass through line 77 into heat exchanger 66 giving up some of the heat in the effluents to the recycle gas by indirect heat exchange. From heat exchanger 66, the mixed effluent passes through line 78 to indirect heat exchanger 79 wherein some heat is given up by the mixed effluent to the water entering the heat exchanger 79 from pipe 48 by means of pipe 85. The water leaves heat exchanger 79 through pipe 86 and flows to steam drum 47. The mixed effluent leaves indirect heat exchanger 79 through line 80 and enters indirect heat exchanger 54 wherein the mixed effluent gives up heat to the incoming charge stock. The mixed effluent leaves heat exchanger 54 by line 81 and passes through cooler 82. From cooler 82 the mixed effluent passes through line 83 to liquid-gas separator 84.

In separator 84 the make gas and recycle gas rise therein and leave separator 84 by pipe 108. The condensed hydrocarbons leave separator 84 by line 88. The make gas and recycle gas are compressed in gas compressor 86 to a pressure sufficient that with the usual losses a pressure of about 15 to 600 p. s. i. a. preferably about 100-300 p. s. i. a. is maintained in reactor 24. The compressed gas leaves the compressor through pipe 87 and is mixed with the condensed hydrocarbons from separator 84 in line 88. The mixture of compressed gas and condensed hydrocarbons passes through line 89 into cooler 90 and through line 91 into recycle gas separator 59.

The recycle gas leaves separator 59 through pipe 60. The condensed hydrocarbons leave separator 59 through line 92 and enter depropanizer 93.

In depropanizer 93, which is of conventional design, the C₁ to C₃ hydrocarbons and absorbed recycle gas separate from the gasoline and leave through pipe 94. The gas flows through pipe 94 to pipe 63 where it is mixed with make gas from absorber 107. The mixed gases pass through pipe 63 to fuel gas storage or holder 64.

The depropanized reformate leaves depropanizer 93 by line 95 and enters primary re-run tower 96 of any suitable design in which a substantial portion of the gasoline in the reformate is flashed overhead as a gasoline containing substantially no polymer. The flashed gasoline containing no substantial amount of polymer leaves re-run tower 96 through line 97 and passes to storage 101. The bottoms from re-run tower 96 passes through line 98 to secondary re-run tower 99. In secondary re-run tower, which is of any suitable type, there is a separation of gasoline of required endpoint from polymer. The gaso-

line passes from secondary re-run tower 99 through line 100 to gasoline storage 101. The polymer leaves secondary re-run tower 99 through line 102 and passes to polymer storage 103.

On some light charge stocks, the stabilizer or depropanizer bottoms can be used for motor gasoline blending without further processing other than caustic washing. However, when charging naphthas of 400° F. or higher endpoint, or when charging naphthas containing substantial amounts of cracked materials, the stabilizer bottoms contain a small amount, about 1 per cent, of polymer which is substantially all aromatic compounds boiling in the range of 400° to 700° F.

Referring now to Figure 2. Two reactors are illustrated in Figure 2 which can replace reactor 24 of Figure 1 and can be used in conjunction with the auxiliary equipment illustrated in Figure 1 in accordance with the principles of the present invention. Therefore, the use of the reactors illustrated in Figure 1 will be described without a discussion of the treatment of the reactor effluents since that has been discussed in conjunction with the discussion of Figure 1.

Active catalyst is accumulated in reactor catalyst feed bin 111 and is introduced into reactor 124 through any suitable device whereby solid particles can be transferred from a zone at a given pressure to a zone at higher pressure. Such a reactor sealing and catalyst transfer device is illustrated in Figure 2 as a pressuring lock formed between gas-tight valves 112 and 114.

The reactor sealing and catalyst transfer device operates in a cyclic manner and comprises gas-tight valves 112 and 114 and pressuring chamber 113. The cycle is as follows: With gas-tight valves 112 and 114 closed, the pressuring chamber 113 is purged with an inert and/or non-flammable gas such as flue gas introduced from a source not shown through pipes 115 and 116 with valve 119 closed and valve 117 open. The purge is vented to a flare not shown through pipes 120 and 121 with valve 123 closed and valve 122 open. After purging, gas-tight valve 112 is opened and catalyst introduced into pressuring chamber 113 until the chamber is filled to a predetermined level. Gas-tight valve 112 is then closed. Valves 117 and 122 are closed and valve 119 opened. A pressuring gas such as recycle gas drawn from a source not shown through pipes 165, 118 and 116 is introduced into pressuring chamber 113 until the pressure therein is at least as high as that in reactors 124 and 124a. Gas-tight valve 114 then is opened and the catalyst flows into surge chamber 204. Valve 114 is closed and valve 123 opened and the residual gas in chamber 113 vented to a flare not shown through pipe 120 until the pressure in chamber 113 is as low as that of reactor catalyst feed bin 111. This completes the cycle.

The catalyst flows from surge chamber 204 downwardly in reactor 124 as a substantially compact column counter-current to the upwardly flowing vapors of the charge mixture introduced into reactor 124 through line 170 and its associated distributor.

The catalyst leaves reactor 124 carrying the excess heat transmitted thereto from the vapors of the charge mixture and passes through conduit 200 into reactor 124a as a substantially compact column. In the top of reactor 124a the downwardly flowing catalyst encounters the vapors of charge mixture introduced into reactor 124a through line 170a and its associated distributor. The catalyst and vapors of the charge mixture flow downwardly concurrently through reactor 124a, the catalyst leaving the reactor and passing through catalyst flow control device 125 and surge tank 126 to a reactor sealing and catalyst transfer means of any type suitable for transferring solid particles from a zone of given pressure to a zone of lower pressure.

In Figure 2 the aforesaid reactor sealing and catalyst transfer device is illustrated as a pressure lock similar to that at the top of reactor 124 and operating in a

similar cyclic manner as follows: With gas-tight valves 127 and 128 closed, depressurizing chamber 129 is purged with an inert and/or non-flammable purge gas such as flue gas drawn from a source not shown through pipe 130 under control of valve 132 and with valves 133 and 136 closed introduced into depressurizing chamber 129 through pipe 131. The purge is vented to a flare not shown through pipe 134 with valve 137 open. After purging, valves 132 and 137 are closed, valve 133 is opened and a suitable pressuring gas such as recycle gas drawn through pipe 165 from a source not shown is introduced through pipes 131 and 138 into chamber 129 until the pressure therein is about equal to that in surge tank 126. Valve 133 is closed and gas-tight valve 127 is opened and catalyst flows from tank 126 into depressurizing chamber 129 to fill chamber 129 to a predetermined level. Gas-tight valve 127 is closed and valve 136 open and the pressuring gas in chamber 129 vented to a flare not shown through pipes 134 and 135. Gas-tight valve 128 is then opened and the catalyst flows out of chamber 129 into surge chamber 205 and thence to chute 139. This completes the cycle.

The catalyst which has become deactivated or spent through contact with the vapors of the charge mixture or mixtures in passage through reactors 124 and 124a flows through chute 139 to any suitable catalyst transfer means such as a gas-lift or the like or an elevator as illustrated in Figure 1 whereby the spent catalyst is transferred to a kiln of suitable design wherein the spent catalyst is reactivated by burning off the carbonaceous deposit thereon in a stream of combustion supporting gas such as air.

The catalyst passes through the kiln in which the carbonaceous deactivating deposit is burned off to provide reactivated catalyst and is transferred to reactor catalyst feed bin 111 ready to begin another cycle through the reactors 124 and 124a.

For simplicity of illustration and description, the reactors 124 and 124a have been shown in Figure 2 as treating the same charge stock. Those skilled in the art will recognize that two different charge stocks can be treated, one in reactor 124 and the other in reactor 124a. A charge stock is drawn from a source not shown, passes through an absorber and heat exchanger as illustrated in Figure 2 and enters furnace 156 through line 155. The charge stock, say a naphtha, is heated in furnace 156 to a temperature below a thermal reforming temperature. The heated charge stock leaves furnace 156 through line 157 and passes into line 170 under control of valve 172.

Recycle gas drawn from a source not shown through line 165 is heated in furnace 168 to a temperature such that when passed through pipe 169 and mixed with charge stock in line 170 in the ratio of about 1 to about 15 mols, preferably about 2 to about 5 mols of recycle gas per mol of charge stock, the temperature of the charge mixture so formed will be sufficiently high to supply a preponderant portion of the heat required for reforming in both zones, such that the ratio of vapor stream heat capacity to catalyst stream heat capacity in reactor 124 shall be about 40-0.7 and preferably about 25-0.9 and the temperature of the charge mixture is about 850° F. to about 1080° F. and preferably about 960° F. to about 1060° F.

The charge mixture in line 170 then passes through lines 170 and 170a and the associated distributors not shown into reactors 124 and 124a. In Figure 2 the catalyst volumes in both reactors 124 and 124a are shown as about equal. The distribution of the vapors of charge mixture between reactors 124 and 124a is controlled and regulated in a manner similar to that employed in conjunction with reactor 24. That is to say, the distribution of charge mixture to reactors 124 and 124a is controlled and regulated by throttling devices 173 and 174 which can be throttle valves of conventional design. Throttling devices 173 and 174 are

set so as to cause about 25-95 percent, preferably about 50 to about 80 percent of the vapors of charge mixture to pass through reactor 124 and the balance through reactor 124a.

The vapors of charge mixture flow upwardly in reactor 124 counter-current to the downwardly flowing substantially compact column of catalyst. The vapors of reformat, make gas and recycle gas leave reactor 124 through line 175 under control of throttle device 173 pass through the various heat exchangers shown in Figure 1 in combination with the effluent from reactor 124a when there is no need to keep the two reformates separate and no need to keep the two gas mixtures separate. However, under some conditions higher octane gasoline is produced in one reactor than in the other. In addition, under some conditions it is advantageous to keep the gaseous effluents separate. Such is provided for in Figure 2 as illustrated. That is to say, the effluent from reactor 124 flows through line 175, throttling device 173, various heat exchangers and cooler 182 to separator 184. In separator 184 the uncondensed gases leave the separator by way of pipe 160 while a portion or all of the gas is bled off through pipe 162 to fuel gas storage or a flare not shown under control of valve 190. The condensed hydrocarbons are drawn off from separator 184 through line 192 and passed to suitable stabilizing and re-run towers or similar fractionating and treating operations as shown in Figure 1.

The charge mixture vapors enter reactor 124a through line 170a and its associated distributor and pass downwardly concurrently with the downwardly flowing substantial compact column of reforming catalyst.

The effluent i. e., reformat, make gas and recycle gas leave reactor 124a through line 176 under control and regulation of throttling device 174. The effluent passes through the various heat exchangers illustrated in Figure 1 to cooler 182a and separator 184a.

In separator 184a the uncondensed gases leave through pipe 160a and mix with the uncondensed gas from reactor 124 in pipe 191 ready for use as recycle gas. All or a portion of the gases leaving separator 184a can be bled to fuel gas storage or a flare, not shown, as required or desired through pipe 162a under control of valve 190a.

The condensed hydrocarbons in separator 184a are passed through line 192a to stabilizing, fractionating or other equipment as shown in Figure 1.

In Figure 3 is shown in a schematic manner a reactor 224 provided with a plurality of charge mixture inlets whereby the complementary volumes of two reforming zones can be varied over a relatively wide range. Thus, when the vapors of the charge mixture enter reactor 224 through manifold branch "a" and its associated distributor not shown, the reactor is divided into two reforming zones wherein the upper zone has a catalyst volume of 25 per cent of the total while the lower zone has a catalyst volume 75 per cent of the total. Similarly, when the vapors of the charge mixture enter reactor 224 through manifold branch "d" and its associated distributor not shown, the reactor is divided into two reforming zones wherein the upper zone has a catalyst volume of 75 per cent of the total while the lower zone has a catalyst volume of 25 per cent of the total. Those skilled in the art will understand that reactor 224 can be provided with as many vapor inlets as the structure permits and is considered desirable.

Reactor 224 is provided with a reactor sealing and solid particle transfer means whereby the particles of active catalyst are transferred from a zone of given pressure, bin 211 to a zone of higher pressure, reactor 224. As illustrated said reactor sealing and solid particle transfer means is a pressure lock similar to that illustrated in Figure 1 and operating in a similar cycle manner. Valves 212 and 214 are gas-tight valves and 213 is a pressuring chamber. Purge gas is introduced into chamber 213 through pipes 215 and 216 under control of valve 217 and vented through pipes 220 and 221 under

control of valve 222. Pressuring gas is drawn from pipe 265 through pipes 218 and 216 under control of valve 219 and introduced into chamber 213. Pressuring gas is vented from chamber 213 through pipe 220 under control of valve 223.

Catalyst enters surge chamber 304 from gas-tight valve 214 and passes downwardly as a substantially compact column into reactor 224 and through reactor 224 counter-current to the charge mixture vapors in that portion of the reactor above the charge mixture inlet and concurrently with the charge mixture vapors in that portion below the charge mixture inlet to leave reactor 224 through catalyst flow control device 225, surge tank 226 and a reactor sealing and solid particle transfer device whereby the particles of spent or deactivated catalyst are transferred from a zone of high pressure to a zone of lower pressure. The reactor sealing and solid particle transfer means illustrated in Figure 3 comprises a depressuring lock similar to that shown in Figure 1 formed by gas-tight valves 227 and 228 and depressuring chamber 229. The depressuring lock operates on a cycle similar to that described in conjunction with Figure 1.

Purge gas is introduced into depressuring chamber 229 through pipes 230 and 231 under control of valve 232 and vented to a flare not shown through pipes 234 and 235 under control of valve 236. Pressuring gas such as recycle gas is drawn through pipes 238 and 231 under control of valve 233 and introduced into chamber 229. The pressuring gas is vented to a flare, not shown, through pipe 234 under control of valve 237.

The spent catalyst flows through valve 228 into surge tank 305 and thence to chute 239 and thence to a catalyst transfer device not shown whereby it is transferred to a kiln or regenerator, not shown, such as illustrated in Figure 1 or of any other suitable type whereby the deactivating carbonaceous deposit on the spent catalyst can be burned off in a stream of combustion supporting gas such as air. The reactivated catalyst is then returned to reactor catalyst feed bin or hopper 211.

Charge stock such as a petroleum naphtha in line 255 is heated in furnace 256 to a temperature above the reforming temperature but below the thermal reforming temperature. Recycle gas in pipe 248 enters furnace 268 wherein it is heated to a temperature such that when mixed with charge stock in the ratio of 1 to 15, preferably about 4 to 10 mols of recycle gas per mol of naphtha, the charge mixture vapors will have a temperature of about 850° to about 1080° F. and preferably about 960° to about 1060° F. and about 20° to about 200° F. above the average reactor temperature. The heated recycle gas passes through pipe 269 under control of valve 271 to line 270. Heated charge stock leaves the furnace through line 257 under control of valve 272 and enters line 270 where it is mixed with heated recycle gas.

Line 270 acts as a manifold from which spaced apart branches "a," "b," "c" and "d" conduct the charge mixture to spaced apart associated distributors not shown. Manifold branches "a," "b," "c" and "d" are provided with valves 270a, 270b, 270c and 270d. The charge mixture is introduced into the reactor through any one of the branches "a," "b," "c" and "d" or others, not shown. A portion of the vapors of the charge mixture flows upwardly counter-current to the downwardly flowing substantially compact column of catalyst in the zone above the inlet through which the charge mixture is introduced into the reactor and downwardly concurrent with the downwardly flowing substantially compact column of catalyst through the zone below the charge mixture inlet.

The distribution of charge mixture between the zone above the charge mixture inlet and the zone below the charge mixture inlet is regulated and controlled by throttling devices 273 and 274 in effluent lines 275 and 276 respectively. Throttling devices 273 and 274 serve the purpose of the throttle valves 73 and 74 in Figure 1.

The effluent from the upper zone leaves reactor 224 through line 275 passes through various heat exchangers and finally condenser 282.

The effluent from the lower zones leaves reactor 224 through line 276 passes through various heat exchangers and finally condenser 282a.

Those skilled in the art will understand that, when the gasolines from both reforming zones in reactor 224 are of substantially the same octane rating and it is not necessary nor desired to discard a part of all of the gas from one zone, the effluents from both zones can be combined as in Figure 1 and treated together.

As illustrated in Figure 3 the effluent from the two zones are treated separately in separators 284 and 284a. The condensed hydrocarbons from separators 284 and 284a leave the separators through lines 292 and 292a respectively to fractionating equipment and storage such as illustrated in Figure 1.

The uncondenser vapors in separators 284 and 284a leave the separators through lines 260 and 260a respectively. When desired, a portion or all of the gases leaving either separator 284 or 284a can be bled to fuel, or a flare, not shown, through pipes 262 and 262a under control of valves 290 and 290a.

Figure 4 provides a schematic illustration of the application of the principles of the present invention to the treatment of two charge stocks. The course of the catalyst through the reactor 324 and the kiln, not shown, is the same as more fully discussed in conjunction with Figure 1. The fractionation and stabilization of the reformate is carried out in a manner similar to that described hereinbefore. Thus, active catalyst is stored in reactor catalyst feed bin 311 and is introduced into reactor 324 through any suitable reactor sealing and catalyst transfer means whereby solid particles in a zone of given pressure are transferred to a zone of higher pressure. Such a sealing and catalyst transfer means is illustrated in Figure 4 as a lock system operating in a cyclic manner as more fully described in conjunction with Figure 1. That is to say, the catalyst transfer means comprises gas-tight valves 312 and 314 and pressuring chamber 313. A non-flammable and/or inert gas such as flue gas is used to purge pressuring chamber 313. The purge gas is drawn from a source not shown through pipes 315 and 316 under control of valve 317 into chamber 313 and vented therefrom through pipes 320 and 321 under control of valve 322, valves 319 and 323 being closed. After purging chamber 313 catalyst is admitted thereto until chamber 313 is filled to a pre-determined level. Chamber 313 is then pressurized with gas-tight valves 312 and 314 closed and valves 317, 322 and 323 closed. The pressuring gas is usually recycle gas drawn from a source not shown through pipes 348, 365, 318 and 316 and introduced into chamber 313 until the pressure therein is at least that of reactor 324. Valve 314 is then opened and the catalyst flows into surge chamber 344. Valve 314 is closed and the cycle completed.

The catalyst flows from surge chamber 344 downwardly through reactor 324 as a substantially compact column counter-current to the upwardly flowing reactant vapors in the upper zone (defined hereinafter) and concurrently with the reactant vapors in the lower zone (defined hereinafter). During its passage through the reforming zones, the catalyst becomes contaminated with a carbonaceous deposit which decreases the catalyst activity and the catalyst is then denominated spent catalyst.

The spent catalyst leaves the reactor 324 through catalyst flow control device 325. Catalyst flow control device 325 is of any suitable type such as a throttling valve. From the catalyst flow control device the catalyst passes into surge tank 326 and thence to a reactor sealing and solid particle transfer means whereby the catalyst particles can be transferred from a zone of given pressure to a zone of lower pressure. Of course, when the regenerator

or kiln is operating at the same pressure as the reactor, such a catalyst transfer means usually is not required.

The catalyst transfer means illustrated in a schematic manner in Figure 4 is a depressuring lock such as illustrated in Figure 1 and discussed in more detail in conjunction therewith.

The catalyst transfer means comprises gas-tight valves 327 and 328 and depressuring chamber 329. The catalyst transfer means operates cyclically as follows: Purge, pressurize, fill, depressurize, empty. Purge gas is drawn from a source not shown through pipes 330 and 331 with valve 333 closed and valve 332 open. The purge is vented to a flare not shown through pipes 334 and 335 with valve 336 open and valve 337 closed. The chamber 329 is pressurized with recycle gas to the pressure existing in surge tank 326 drawn from a source not shown through pipes 348, 338 and 331 with valves 332, 336 and 337 closed and valve 333 open, gas-tight valves 327 and 328 being closed. Chamber 329 is filled with catalyst to a pre-determined level by opening gas-tight valve 327. After chamber 329 has been filled to a pre-determined level, gas-tight valve 327 is closed and the pressure in chamber 329 reduced to that of the kiln, not shown, by venting the gas therein to a flare not shown through pipe 334 under control of valve 337. Gas-tight valve 328 is then opened and the catalyst flows into surge chamber 345 and thence to chute 339. The cycle is then completed.

The catalyst flows along chute 339 to any suitable catalyst transfer device, not shown, whereby the catalyst is transferred to the kiln or regenerator.

The kiln is of any suitable type whereby the carbonaceous deposit is burned off in a stream of combustion supporting gas such as air. By removal of the carbonaceous deposit the catalyst is reactivated. The catalyst leaves the kiln as activated catalyst and is transferred to reactor catalyst feed bin 311 by any suitable catalyst transfer device such as a gas-lift or the like, an elevator etc.

Before discussing the path of the reactants through the reactor, it is believed well to discuss the formation of upper and lower reforming zones in reactor 324.

The upper reforming zone is that portion of the reactor above the particular pair of charge mixture inlets and associated distributors, not shown, being used at any time. The lower reforming zone is that portion of the reactor below the particular pair of charge mixture inlets and associated distributors, not shown, being used at any particular time. Thus, as illustrated, reactor 324 is provided with a plurality of spaced apart pairs of charge mixture inlets, *a*-403, *b*-404, *c*-405 and *d*-406, and other associated distributors not shown. The pairs of charge mixture inlets and associated distributors not shown divide reactor 324 into an upper zone of 25 per cent of the catalyst volume and a lower zone of 75 per cent of the catalyst volume when pair *a*-403 is used. The upper reforming zone in reactor 324 is 72 per cent of the catalyst volume and the lower reforming zone is 28 per cent of the catalyst volume when charge mixture inlet pair *d*-406 and the associated distributors is used. The other pairs divide the reactor into upper reforming zones of 30 per cent and 47 per cent of the catalyst volume with corresponding lower reforming zones of 70 per cent and 53 per cent.

In treating two charge stocks in accordance with the principles of the present invention, one charge stock is drawn from a source, not shown, through an absorber when desired and various heat exchangers and introduced into furnace 356 by means of line 355. In furnace 356 the charge stock is heated to a temperature below the thermal reforming temperature. The heated charge stock leaves the furnace through line 357 and passes into line 370.

Recycle gas which, when the reforming reaction is carried out in the presence of hydrogen comprises about 25 per cent to about 80 per cent, preferably about 35 per cent to about 60 per cent hydrogen, balance C₁ to C₆ hydrocarbons is drawn from a source, not shown,

through pipes 348 and 349 and heated in furnace 368 to a temperature such that when mixed with the charge stock in the ratio of about 1 to about 15 mols, preferably about 4 to about 10 mols of gas per mol of charge stock, provides a charge mixture carrying into the upper reforming zone an amount of heat in excess of that required in the upper zone for the reforming reaction taking place therein.

10 A second charge stock is drawn through line 400 from a source, not shown, and heated in furnace 401 to a temperature below the thermal reforming temperature. The heated second charge stock leaves furnace 401 by means of line 402.

15 The heated recycle gas leaves furnace 368 by pipe 369 and passes through pipe 394 under control of valve 395 to line 370 where it is mixed with heated charge stock 1 in the ratio set forth hereinbefore to form a charge mixture 1.

20 The heated recycle gas in pipe 369 passes through pipe 393 under control of valve 371 and mixes with charge stock 2 in lines 402 to form charge mixture 2.

25 It is to be noted that recycle gas can be mixed with both charge stocks in the same or different molar ratios within the limits of about 1 to about 15, preferably about 4 to about 10 mols of gas per mol of naphtha. When reforming in the presence of hydrogen, the recycle gas comprises about 25 per cent to about 80 per cent, preferably about 35 per cent to about 60 per cent hydrogen, balance C₁ to C₆ hydrocarbons and is mixed with the two charge stocks in the same or different molar ratios within the limits of about 1 to about 8, preferably about 2 to about 5 mols of hydrogen per mol of charge stock. The average molecular weight of the charge stocks being determined in the usual manner from the 30 ASTM distillation curve.

35 The charge mixture 1 in line 370 enters reactor 324 through one of the branches *a*, *b*, *c*, or *d* of line 370 under the control of valves 370*a*, 370*b*, 370*c* or 370*d* respectively dependent upon the octane rating required 40 in the gasoline produced in the upper reforming zone, the refractoriness of the charge stock and similar considerations.

45 Whichever inlet *a*, *b*, *c* or *d* which is selected for introduction of charge mixture 1 into reactor 324 the other member of the pair is used to introduce charge mixture 2 into the reactor. Thus, for the purpose of illustration and description, the charge mixtures will be described as entering reactor 324 through charge mixture inlets *c* and 405 and the associated distributors not shown.

50 The distributors associated with the pairs of charge mixture inlets are of any suitable type whereby the charge mixture can be distributed over substantially the whole cross-section of the reactor.

55 Charge mixture 1 in line 370 passes through branch or charge mixture inlet *c* and its distributor. The vapors thereof flow upwardly through the portion of the reactor above inlet *c* countercurrent to the downwardly flowing substantially compact column of catalyst and out of the upper reforming zone through line 375 under control of throttling means 373 of any suitable type whereby the volume of reformed and associated gases can be controlled and regulated. Such control and regulation of the effluent from the upper reforming zone controls the quantity of charge mixture 1 which passes through the upper reforming zone.

60 Charge mixture 2 enters reactor 324 through branch or charge mixture inlet 405 and its distributor not shown of any suitable type whereby the charge mixture is distributed over substantially the entire cross-section of reactor 324. The vapors of charge mixture 2 flow downwardly concurrent with the downwardly flowing substantially compact column of catalyst. The effluent from the lower reforming zone leaves the lower reforming zone through line 376 under control of throttling device 70 374 which is of any suitable type such as a throttle valve

whereby the volume of effluent passing through line 376 is regulated and thereby the quantity of charge mixture passing through the lower reforming zone is regulated.

The effluent from the upper zone and that from the lower zone can be mixed when gasolines of substantially the same octane rating are produced. The mixed effluents then be passed through the various heat exchangers and thence to stabilizing and fractionating equipment such as illustrated in Figure 1.

When producing gasolines of different octane ratings the effluents are kept separate. Thus, the effluent from the upper reforming zone passes through line 375 and various heat exchangers to cooler 382 from which the cooled effluent passes through line 383 to liquid gas separator 384.

The condensed hydrocarbons in separator 384 are withdrawn through line 392 and passed to suitable stabilizing and fractionating equipment.

The gases separated in separator 384 leave through pipe 369 to recompression and recycle. When it is desired, the whole or a part of the gases from separator 384 can be vented to a flare or fuel storage through pipe 362 under control of valve 390.

In a similar manner the effluent from the lower reforming zone leaves reactor 324 through line 376 under control of throttling device 374 and passes through various heat exchangers to cooler 382a. The cooled effluent passes through line 383a to separator 384a. In separator 384a the condensed hydrocarbons separate and are withdrawn through 392a to stabilizing and fractionating equipment such as illustrated in Figure 1.

The gases separated in separator 384a pass through pipe 369a to recompression and recycle with or without contact with incoming charge stock. When desired, a portion or all of the gases from separator 384a can be vented to a flare or fuel gas storage through pipe 362a under control of valve 390a.

In Figure 5 is provided a schematic representation of a multi-inlet and consequently multi-bed or multi-zone reactor in a simplified form for ease of representation and discussion. Those skilled in the art will appreciate that while the reactor as represented is shown with only two inlets positioned at approximately the vertical midpoint of the reactor sufficient inlet pairs of groups can be provided to permit division of the catalyst bed as illustrated in Figures 3 and 4.

The reactor illustrated in Figure 5 provides a means for operating each reforming zone of the reactor at a different recycle ratio simultaneously. At high catalyst to oil ratios it is often desirable and under some conditions, such as need for operation at low coke lay-down levels, necessary to be able to maintain a higher recycle gas to charge stock ratio in one reforming zone than in the other.

Since the passage of the reforming catalyst successively through the reforming zones and thence to the kiln or regenerator has been described in the discussions of Figures 1, 3 and 4 and since the passage of the reforming catalyst through the reactor illustrated in Figure 5 is the same, it is believed unnecessary to repeat the description provided hereinbefore and only necessary to discuss and describe the flow of the charge stock and recycle gas through the reactor and associated after-treatment.

Thus a charge stock comprising a mixture of hydrocarbons containing hydrocarbons convertible to aromatic hydrocarbons such as a naphtha is drawn through line 455 to furnace 456. The charge stock is heated in furnace 456 to a temperature below a thermal reforming temperature. Of course, two charge stocks could be treated simultaneously as shown in Figure 4 but to avoid prolixity and to simplify the following discussion and description the treatment of only one charge stock will be given. The heated charge stock at at least a catalytic reforming temperature and below a thermal reforming temperature

leaves furnace 456 via line 457 under control of valve 472 and enters line 470.

Recycle gas, which when reforming a charge stock in the presence of hydrogen, comprises about 25 to about 80 and preferably about 35 to about 60 per cent hydrogen and the balance C₁ and C₆ hydrocarbons, is drawn through pipe 467 and heated in furnace 468 to a temperature such that when mixed with the charge stock to provide a charge mixture the vapors of which enter the reactor at a temperature at least 20° F. and preferably at least 40° F. above the average temperature in the upper reforming zone and supplies at least 75 per cent of the required heat of reaction. The heated recycle gas leaves furnace 468 via pipe 469.

Two methods of supplying different amounts of recycle gas to the two reforming zones can be employed. For example, the charge stock can be split as by passing charge stock through lines 470 and 507 under control of valves 472 and 508 respectively and introducing recycle gas into each portion of charge stock through pipes 509 and 504 under control of valves 471 and 506 respectively or the charge stock can be introduced through one line 470 or 507 admixed with recycle gas therein and additional recycle gas, introduced into the other reforming zone 25 through the other inlet.

For example, heated charge stock can be passed through lines 470 and 507 and heated recycle gas admixed with the charge stock in both lines 470 and 507 to provide charge mixtures having different ratios of recycle gas to charge stock of about 1 to 15 mols of gas to 1 mol of charge stock by admitting heated recycle gas from pipe 509 into line 470 in an amount to provide a charge mixture having, for example, a recycle gas to charge stock ratio of say about 6 to about 8 mols of recycle gas to 1 mol of charge stock and admitting heated recycle gas from pipe 504 into line 507 in an amount to provide a charge mixture having, for example, a recycle gas to charge mixture ratio of about 10 to 12. On the other hand, heated charge stock can be passed through line 507 only, heated recycle gas admitted from pipe 504 in an amount to provide a charge mixture having, for example, a recycle gas to charge mixture ratio of about 4 to 6 mols recycle gas to one mol of charge stock and sufficient heated recycle gas admitted to the lower reforming zone through pipe 509 and line 470 and the associated distributor to raise the recycle gas to charge stock ratio from the existing 4 to 6 mols of recycle gas per mol of charge stock to say 10 to 12 mols of recycle gas per mol of charge stock.

Mixing of the vapors of the upper and lower reforming zones and consequent vitiation of the regulation of the recycle gas to charge mixture ratios at the inlets is obviated by means of the throttling devices 473 and 474 which are of any suitable type whereby control of the volume of effluent passing therethrough is obtained and maintained such as throttling valves.

The reformat from the upper zone U leaves the reactor 424 via line 475 under control of throttling device 473. The reformat from the lower zone L leaves the reactor 424 through line 476 under control of throttling device 60 474. When the reformates from both zones are of the same octane rating, the reformates are mixed in line 477 passed through various heat exchangers, as illustrated in Figure 1 to cooler 482. Thence through line 490 to separator 484 from which the uncondensed effluent passes through pipe 485, a compressor not shown and pipe 487 to line 489 where the compressed uncondensed effluent is mixed with the condensed effluent and passed to the separator, stabilizer and fractionators illustrated in Figure 1.

When the reformates of the upper and lower reforming zones are of different octane ratings, the effluent from upper zone U passes through line 483 to heat exchangers, cooler, etc., such as shown in Figure 1. The effluent from lower zone L under these conditions passes through

line 483a to the heat exchangers, cooler stabilizer etc. shown in Figure 1.

The foregoing discussion has been descriptive of a method of operating a split-flow reactor to provide an upper and a lower reforming zone in which the sensible heat content of the catalyst stream entering the upper reforming zone above the average temperature in the upper zone is not more than about 25 per cent of the heat requirement of the upper reforming zone; the vapor inlet temperature is at least 20° F. and preferably at least 40° F. above the average temperature in the upper reforming zone; when the same charge stock is fed to both the upper and lower reforming zones, the space velocity in the lower zone is not greater than the space velocity in the upper zone; and when two different charge stocks are treated simultaneously and the less refractory stock is fed to the lower zone, the space velocity in the lower zone can be as much as 3 times the space velocity in the upper zone. Accordingly, the present invention provides a method of reforming a mixture of hydrocarbons containing hydrocarbons convertible to aromatic hydrocarbons such as virgin petroleum naphtha, cracked naphtha, and mixtures of straight run and cracked naphtha simultaneously at two different severities or two different charge stocks at two different severities over the same catalyst to obtain two gasoline products of different octane numbers comprising passing a reforming catalyst successively through two reforming zones, passing reactant vapors counter-current to catalyst flow in the first reforming zone and concurrent to catalyst flow in the second reforming zone at rates such that the ratio of the vapor stream heat capacity to the catalyst stream heat capacity ratio is about 0.7 to about 40 and preferably about 0.9 to about 25 in the first reforming zone, heating the charge stock and recycle gas to a temperature such that the charge mixture entering the first reforming zone supplies at least 75 per cent of the required heat of reaction in the top zone and the charge mixture entering the second reforming zone carries less than the heat required for the more severe reforming reaction occurring therein, the temperature in the second reforming zone automatically being higher, the charge mixture entering the first reforming zone carrying an amount of heat in excess of that required for the reaction occurring therein and said excess heat being transferred to the catalyst contact in said first reforming zone and carried into said second reforming zone by said catalyst, and the space velocity in the two reforming zones being controlled so that the reforming reaction is more severe in the second reforming zone than in the first reforming zone.

I claim:

1. A method of reforming hydrocarbons wherein particle-form solid reforming catalyst flows downwardly as a substantially compact column successively through at least two reforming zones under reforming conditions of temperature and pressure and then through a regenerator in a cyclic manner, wherein the catalyst bed in the first reforming zone is about 20 to about 80 per cent of the total volume of catalyst in both reforming zones, wherein a heated charge mixture comprising a substantially completely vaporized charge stock containing hydrocarbons to be reformed and recycle gas is introduced into each reforming zone wherein about 25 to about 95 per cent of the total charge mixture treated in both zones is introduced into said first reforming zone, wherein a major portion of the required heat of reaction in all of said reforming zones is supplied by said charge mixtures without substantial thermal cracking of said charge stock, wherein the ratio of the vapor stream heat capacity of charge mixtures entering said reforming zones to the catalyst stream heat capacity is about 0.5 to about 200, wherein the average space velocity of said charge stock for all of said reforming zones is about 0.1 to about 6.0 and wherein at least one charge stock is heated to a temperature higher than the average

reaction temperature in the first reforming zone but below a temperature at which substantial thermal cracking occurs, recycle gas is heated to a temperature of about 1000° to about 1300° F., mixing said heated charge stock and said heated recycle gas to provide a heated charge mixture having a temperature of at least 850° F. and at least 20° F. above the average temperature in said first reforming zone, introducing particle-form solid reforming catalyst into the first of said reforming zones, flowing said particle-form reforming catalyst downwardly as a substantially compact column through said first reforming zone, regulating the temperature and amount of particle-form solid reforming catalyst introduced into said first reforming zone to supply not more than about 25 per cent of the required heat of reaction therein, introducing said charge mixture into the bottom of said first reforming zone, flowing said charge mixture upwardly through said first reforming zone, regulating the amount and temperature of charge mixture introduced into said first reforming zone to supply heat in excess of the balance of the heat required therein and not supplied by said catalyst and between about 25 and 95 per cent of the total charge mixture introduced into all of said reforming zones, contacting said charge mixture with said reforming catalyst to reform hydrocarbons and to transfer at least a portion of the charge mixture heat to said catalyst column to supply more than about 5 per cent of the heat required in the second reforming zone whereby said reforming catalyst leaves said first reforming zone at a higher temperature than the reforming catalyst inlet temperature of said first reforming zone, withdrawing heated reforming catalyst from the bottom of said first reforming zone, introducing said withdrawn heated reforming catalyst into the top of a second reforming zone without any substantial loss of sensible heat, introducing heated charge mixture into the top of said second reforming zone, flowing said heated withdrawn reforming catalyst as a substantially compact column downwardly through said second reforming zone, flowing said heated charge mixture downwardly in contact with said catalyst column whereby heat transferred from said charge mixture to said catalyst in said first reforming zone supplies more than 5 per cent of the heat required in said second zone, withdrawing vapors from the top of said first reforming zone as a first effluent, withdrawing vapors from the bottom of said second reforming zone as a second effluent, separating liquid hydrocarbons in said first and second effluents from gases, recycling said separated gases to said reforming zones, withdrawing reforming catalyst from the bottom of said second reforming zone, regenerating said withdrawn catalyst, recycling said regenerated catalyst to said first reforming zone.

2. The method of reforming hydrocarbons as set forth and described in claim 1 wherein the charge stock is a petroleum fraction.

3. The method of reforming hydrocarbons as set forth and described in claim 1 wherein the charge stock is petroleum naphtha and the recycle gas contains at least 25 per cent hydrogen.

4. The method of reforming hydrocarbons as set forth and described in claim 1 wherein the charge stock introduced into the second reforming zone is not the same charge stock which is introduced into the first reforming zone and the recycle gas contains at least 25 per cent hydrogen.

5. The method of reforming hydrocarbons as set forth and described in claim 1 wherein the same petroleum naphtha charge stock is introduced into both reforming zones, the space velocity in the second reforming zone is not greater than the space velocity in the first reforming zone and the recycle gas contains at least 25 per cent hydrogen.

6. The method of reforming hydrocarbons as set forth and described in claim 1 wherein the petroleum naphtha

charge stock treated in the second reforming zone is less refractory than the charge stock treated in the first reforming zone, the space velocity in the second reforming zone is up to three times the space velocity in the first reforming zone and the recycle gas contains at least 25 per cent hydrogen.

7. The method of reforming hydrocarbons as set forth and described in claim 1 wherein the volume of catalyst in the first reforming zone is greater than the volume of catalyst in the second reforming zone, the same volume of charge mixture is passed through both reforming zones

5

10

and the recycle gas contains at least 25 per cent hydrogen.
